CLOSURE DEVICE FOR MAILING TUBES

Willie D. Glass, Hopewell, Va.

Application April 8, 1939, Serial No. 266,826

1 Claim. (Cl. 229—93)

This invention relates to a means for closing the ends of mailing tubes and the like, and it consists in the constructions, arrangements and combinations herein described and claimed.

5 It is an object of the invention to provide a closure means for mailing tubes of a cheap and simple construction, readily attachable to the ends of a tube and bendable to a position over the openings of the tube for securing of material therewithin.

10 It is also an object of the invention to provide a novel means for securing the free ends of the closure means, as well as permitting ready disengagement of ends for removal of material within the tube.

15 Additional objects, advantages and features of invention will be apparent from the following description and accompanying drawing, wherein

Figure 1 is a perspective view of a tube having my closure means applied.

Figure 2 is a fragmentary sectional view illustrating the securing of the device to a tube.

Figure 3 is a perspective view of one of the strips employed in the closure device.

20 Figure 4 is a similar view of another of the strips.

Figure 5 is an edge view thereof.

25 There is illustrated a mailing tube 10 of usual open-ended construction, adjacent the ends of which there are secured three sheet metal strips 11, 12, and 13.

The strips 11 and 12 are identical in construction and comprise integral struck-out tongues 14 adjacent one end, the opposite end being 30 provided with an aperture 15. The strip 13 is similarly provided with tongues 14' adjacent one end, the other end terminating in a reduced end portion 16, the portion 16 being of a size freely passing through the apertures 15 of the strips 11 35 and 12.

40 The strips 11, 12 and 13 are secured to the

tube by forcing the tongues 14—14' through the material of the tube and clinching the tongues upon the inner side, as clearly shown in Figure 2.

The strips 11, 12 and 13 are arranged symmetrically about the end of the tube and of a length projecting therebeyond so as to overlap at a point axially of the tube, when bent thereover. The strip 13 will preferably be bent into position first with the portion 16 bent at right angles, as indicated by dotted lines in Figure 5. The strips 11 and 12 are next bent into position, the apertures 15 receiving the end portion 16 therethrough. The end 16 is finally bent to snugly abut the uppermost strip 11 or 12, as the case may be.

From the foregoing, it will be seen that material within the tube will be securely retained, yet permitting ready disengagement between the strips for removal of the material.

While I have shown and described a preferred embodiment of the invention, this is illustrative only, and I consider as my own all such modifications in structure as fairly fall within the scope of the appended claim.

I claim:—

A closure for a mailing tube or the like comprising strip members arranged symmetrically about the open end of the tube, each strip member having tongues for securing to the tube adjacent the ends thereof, said strip members being of a length to present their free ends in overlapped position axially of the tube when bent over the open end thereof, certain of said strips having an aperture adjacent their free ends and one of said strips having a reduced portion for engagement through aligned apertures, said reduced portion being bendable for securing of the strips.

WILLIE D. GLASS.
